UNITED STATES PATENT OFFICE.

ALLISON M. MARSHALL, OF STIGLER, OKLAHOMA.

SHINGLE-MACHINE.

1,261,581.

Specification of Letters Patent.

Patented Apr. 2, 1918.

Application filed October 20, 1916. Serial No. 126,738.

To all whom it may concern:

Be it known that I, ALLISON M. MARSHALL, a citizen of the United States, residing at Stigler, in the county of Haskell and State 5 of Oklahoma, have invented new and useful Improvements in Shingle-Machines, of which the following is a specification.

This invention relates to shingle machines of that general class or type in which a reciprocal carriage is utilized to carry the shingle blocks across a circular saw which is set or mounted for rotation in an approximately horizontal plane, means being employed whereby the blocks will be tilted at 15 the limit of the movement in each direction, shingles being cut from the blocks as the carriage moves in either direction.

One object of the invention is to simplify and improve the construction of the carriage 20 and the block tilting means.

A further object of the invention is to provide stationary supports for the shingle blocks whereby the shingle blocks will be oppositely tilted at opposite sides of the saw, 25 means being also provided whereby the shingle blocks are properly clamped and retained with respect to the carriage.

With these and other ends in view which will readily appear as the nature of the invention is better understood, the same consists in the improved construction and novel arrangement and combination of parts which will be hereinafter fully described and particularly pointed out in the claim.

In the accompanying drawings has been illustrated a simple and preferred form of the invention, it being, however, understood that no limitation is necessarily made to the precise structural details therein exhibited, 35 but that changes, alterations and modifications within the scope of the claim may be resorted to when desired.

In the drawings,—

Figure 1 is a top plan view of a shingle machine constructed in accordance with the invention, the carriage being shown positioned at one limit of its movement.

Fig. 2 is a longitudinal sectional view taken on the line 2—2 in Fig. 1.

Fig. 3 is a transverse sectional view taken on the line 3—3 in Fig. 1, through the saw and looking in the direction of the carriage.

Fig. 4 is a transverse sectional view taken on the line 4—4 in Fig. 1 through the main 55 frame and the carriage.

Fig. 5 is a perspective view showing the

carriage detached from the frame of the machine.

Corresponding parts in the several figures are denoted by like characters of reference. 60

The bed frame A of the machine is of rectangular form, being composed of side members 15 and end members 16. The bed frame may be mounted on legs or supports, portions of which appear at 17, and the side 65 members 15 are provided on their inner faces with track members 18 which are interrupted midway between the ends of the frame, the side members 15 being provided at the points where the track members are interrupted 70 with slots 19 forming outlets through which the greater portion of the sawdust may escape, flues 20 being provided to carry the sawdust to a point of deposit, not shown. The circular saw 21 is mounted for rotation 75 about midway between the sides of the frame.

Supported on cross bars 22 and extending longitudinally of the frame are gage strips 23, 23', said strips being vertically adjustable by means of screws 24. Two such gage strips are arranged at each end of the machine at diametrically opposite sides of the saw arbor, and the gage strips are so arranged, by means of the adjusting screws, 80 that two diagonally opposite strips, designated by 23, will be relatively high, and the remaining two gage strips, 23', which are also diagonally opposite with respect to each other, will be relatively low; that is to say, 85 the gage strips 23 will be arranged in an approximately horizontal plane which is above the approximately horizontal plane in which the gage strips 23' are disposed. The top faces of all the gage strips are disposed in 90 planes below the plane of the circular saw 21. 95

The carriage C which moves along the tracks 18 is of mainly rectangular construction, consisting of a frame comprising side members 25 and end members 26, the latter 100 being connected together by longitudinal frame bars 27. Secured on the under faces of the side members 25 are the guide flanges 28 which extend beyond the outermost faces of the side members, and are adapted to ride 105 on the track members 18. Secured on the under faces of the guide flanges and spaced thereby from the end members 26 beneath which they extend are supporting bars 29, one at each end of the carriage frame, said 110 supporting bars being sufficiently spaced from the lower faces of the end members to

admit the slides 30, said slides constituting clamping members whereby the shingle blocks are clamped and held between the longitudinal frame bars 27. The slides or 5 clamping members 30 are arranged substantially beneath the longitudinal frame bars 27 and each slide serves to clamp the blocks between one of said bars and itself, as will be presently seen.

10 Means are provided for projecting and retracting the slides or clamping members 30 with respect to the inner faces of the longitudinal frame bars, said means comprising longitudinal rock shafts 31 which are 15 supported in bearings on the outer faces of the side members 25 of the carriage, said rock shafts extending terminally slightly beyond the end members of the carriage, where said rock shafts are provided with 20 upwardly extending arms or levers 32 having laterally extending arms 33. The ends of the slides 30 are connected with the carriage by means of toggles composed of links 34, 35 which are flexibly joined together at 25 36, the links 34 being pivotally connected with the slides, and the links 35 being pivotally connected with the carriage at the ends and near the sides of said carriage. A link rod 36' connects the arm 33 of each 30 lever 32 with a toggle link 34, said toggle link being provided intermediate the ends thereof with an eye 37 with which the link rod 36' is flexibly connected.

It will be observed from the foregoing 35 that either rock shaft 31 may be rocked by means of either one of the levers 32 at the two ends thereof and that by such movement the slides 30 may be projected or retracted with respect to the inner faces of the longitudinal frame bars 27 beneath which they 40 slide. Stop members 38 are preferably provided on the ends of the carriage to limit the movement in one direction of the levers 32 to prevent the toggle joints from passing 45 a dead center and thus prevent the retraction of the slides by the pressure of the shingle blocks clamped thereby.

For the purpose of actuating the levers 32 and the parts controlled thereby cam 50 members 38 are provided at the two ends of the frame, said cam members being so disposed that when the carriage approaches the limit of its movement in one direction, the respective levers and rock shafts will 55 be actuated in opposite directions, while when the other limit of the movement of the carriage is approached, the respective rock shafts and levers will be actuated in the opposite directions, so that one slide will 60 be moved into clamping position at one end of the frame and into retracted position at the other end. The parts of the machine are, moreover, so arranged that the slide 30 which is projected to clamping position at 65 each limit of the movement of the carriage

will be the one which is located adjacent to the gage strip 23 which is positioned in a plane below that of the mating gage strip 23.

In the operation of this invention the shingle blocks, designated by S, are piled in 70 the carriage, crosswise thereof, between the longitudinal frame bars 27, said blocks being preferably placed in the carriage while the latter is at a short distance from the limit of its movement in any direction, where the 75 slides 30 may both be retracted, thus permitting the shingle blocks to rest on the gage strips 23, 23' in a slightly tilted position, the extent of the tilt being governed by the adjusting screws 24. When the carriage is 80 now moved to the limit of its movement, one of the slides will be projected by its actuating means in connection with one of the cams 38, thus causing the high ends of the shingle blocks to be clamped between one 85 of the longitudinal frame bars and the slide 30. When the carriage is now moved to the other end of the frame, shingles will be cut from each of the blocks, said shingles dropping below the saw while the shingle blocks 90 remain in position until the position of the slides 30 is reversed by engagement of some of the levers 32 with the cam members 38. The reversal of the slides or clamping members will permit the shingle blocks to drop 95 gravitationally until they rest on the gage strips 23, 23' at that end of the machine, the blocks being thus tilted and supported in a position oppositely inclined to the position previously occupied, and the blocks 100 being clamped in such position while the carriage makes its return movement. The operation is repeated until the blocks are exhausted when the carriage is again charged.

105 For the purpose of imparting reciprocatory movement to the carriage any suitable and well known mechanism may be employed, but such mechanism being no part of the present invention, it has not been 110 illustrated and it does not require to be particularly described.

The levers 32 may be provided at the points where they engage the cam members 38 with anti-friction elements, such as rollers 32'', as illustrated at the right hand end of Fig. 5 of the drawings. The presence of these anti-friction rollers will to some degree facilitate the operation of the device, but such anti-friction elements may be used or 120 dispensed with as may be desired.

Having thus described the invention, what is claimed as new, is:—

In a shingle machine, a bed frame, a circular saw mounted about centrally of the 125 frame, longitudinal gages between the saw and the ends of the frame, said gages being arranged in pairs at the two ends of the frame, means for supporting the gages of each pair at unequal heights, diagonally op- 130

posite gages being supported at substantially the same height, a reciprocatory carriage on said frame having a pair of guide bars thereon spaced apart and adapted to receive 5 the shingle blocks between them, the space between said bars being slightly greater than the width of the blocks, a slide located below each bar, a lever connected with each slide for moving the same horizontally to grip the blocks between itself and one of the bars, 10 and cam means at the ends of the frame for engaging with said levers for retracting one of said slides and projecting the other, said cams acting to move the slides in opposite directions at the end of the machine. 15

In testimony whereof I affix my signature.

ALLISON M. MARSHALL.
